Patented June 18, 1918.

UNITED STATES PATENT OFFICE.

JOHN F. RYAN, OF NEW ROCHELLE, NEW YORK.

TAPE-HANDLING MACHINE.

1,269,749.

Specification of Letters Patent. Patented June 18, 1918.

Application filed February 5, 1918. Serial No. 215,419.

To all whom it may concern:

Be it known that I, JOHN F. RYAN, a citizen of the United States, residing at New Rochelle, in the county of Westchester 5 and State of New York, have invented new and useful Improvements in Tape-Handling Machines, of which the following is a specification.

This invention relates to improvements in 10 tape handling machines. More particularly it is illustrated as applied in apparatus adapted to hold a roll of gummed paper tape in such position that its end can be easily drawn forth, moistened and severed, 15 for uses such as for sealing a package.

It is an object of the invention to provide 20 an improvement in apparatus of the class described such that the tape can be more easily started from a position of rest, and drawn forth, by simple pressure of a person's finger on the top of it; also to provide 25 means by which a full roll can be substituted for an exhausted roll of the same width of tape without disturbing the adjustment of tension, and to do this by a simple manipulation; and also to provide for 30 regularity of tension regardless of the diameter of supply roll and its condition of fullness or exhaustion; and to provide this tension in connection with tape guiding and holding means in such manner as to hold the 35 tape adequately while the operator is tearing it along a blade, from one side to the other of the tape. One embodiment of the 40 invention is shown in the accompanying drawing, but it is to be understood that variations may be made from the particular form illustrated, and that the invention may be employed with tape used for other purposes, whether the strip drawn forth be of 45 dry gummed paper or of other material. It is intended that the patent shall cover, by suitable expression in the appended claims, whatever features of patentable novelty exist in the invention disclosed.

In the accompanying drawings:—

Figure 1 is a side elevation;

Fig. 2 is a plan, with part in section on the line 2—2 of Fig. 1;

Fig. 3 is a side elevation of a portion, on a larger scale, in section on the line 3—3 of Fig. 2;

Fig. 4 is a perspective view of a detail of the tape guide;

Fig. 5 is a front elevation of a fragment, in section on the line 5—5 of Fig. 1; and

Fig. 6 is a side elevation of a fragment, in section on the line 6—6 of Fig. 5.

Referring to the drawings, 10 indicates a base, consisting of a frame made of two longitudinal strips of material standing upright on their edges and joined by a transverse strip at each end. This frame holds an upright standard 11, at one side at its rear, for holding the supply roll 9 of tape; 15 a blade 12 under which the tape passes; and a moistening roll 13 over which the tape passes, the roll being set and partly immersed in water in a tank 14 held by the frame. After a portion of tape has been 20 drawn forth and severed, the latter operation being executed by the operator lifting the tape to the blade and tearing it across the edge of the blade, the tape rests with its forward edge under the forward edge of the 25 severing blade and inaccessible to the fingers of anyone desiring to seize it to draw forth another portion. One of the features of the invention relates to a device for improving the initial feeding of the tape on 30 such an occasion, by providing a bed of rollers 15 over which the tape passes on its way to the blade and moistener. These rollers, journaled in the side pieces of the frame 10, and extending across from one 35 side to the other, are preferably of such diameter, say half of an inch or so, as will permit the arrangement of a number of them in line with their crests close enough together to form a succession of supports 40 for the tape, from one to the other of which it passes without much sagging between or change of direction. They are not necessarily in a straight line. Each roll is preferably knurled, the many small points thus 45 produced tending to engage the paper when the paper is pressed upon it by a yielding substance such as the human finger and yet presenting to the tape such a small area on each, and in total, that there is little 50 strength of adhesion between the rolls and the tape if the tape be adhesive owing to unusual humidity of atmosphere, or if a portion that has been moistened by roll 13 has 55 been later drawn back without being severed. In consequence, a person pressing his finger upon tape lying on this knurled roller, and drawing his finger toward the moistener, finds that the tape moves readily and smoothly with it. The leverage resulting 60 from the difference of diameter between the knurled working surface and the surface

of the axle of a roller is such that the roll turns with great ease, particularly if the axle be lubricated. This device eliminates a fault which has been observed in some machines heretofore constructed, in which the tape rests on, and is fed by finger pressure over, a stationary guide plate, in which cases a tendency of the tape to adhere to the guide plate beneath it has been experienced, especially when that plate has become somewhat rough or rusty, or when the gummed under side of the tape for any reason is inclined to stick, as upon a day of extreme humidity. The invention substitutes a moving surface of non-adhesive character. The rolls are in such proximity to each other that they have the effect of a moving surface, although the surface as a whole stays in its stationary position, notwithstanding the motion. From the smallness of the radius of curvature of the roll elements, three other important results follow, viz: first, portions of the surfaces of the rollers have an inclined face, as it were, toward the direction from which the tape moves, so that the tape, bending under the pressure of a person's finger, is more firmly pressed upon each as the finger reaches each roll in turn; second, the depression of the tape into the space between two rolls bends it so as to detach any parts that may be adhering to a roll, and third, the further surfaces of the rotating elements, which are on the side toward the moistener, are rotated down out of contact with the tape, at a relatively sharp angle therewith and after a contact which is only brief. As it is only at the crests of the rollers that the tape can adhere, when left at rest, and only at the points made by the nurling on the crests, there cannot be any strong permanent adhesion; and as those crests are easily movable about their pivots the tape is easily started forward, even though adhering, or even though rubbing with such friction as would prevent its feeding if it were on a stationary surface; and immediately upon starting it becomes separated by the rotation of the rollers. A person's finger is naturally applied to the upper slopes of the rollers as he draws it toward the moistener while pressing downward on the tape, and as this pressure approaches being normal to that surface it gives a good grip on the tape to start it moving, and at the same time the pressure is in approximately the direction of desired motion. Hence the tape moves forward with the finger, with only the frictional drag which exists at the pivots of the rollers and is self-clearing.

Beyond this feeding contrivance, the tape passes severing means and moistening means.

These may be arranged in any ordinary or suitable manner, so far as the present invention is concerned. The drawings illus-

trate apparatus in which the former precedes the latter and in which the tape passes through a guide-way 8 into contact with the moistener, which is arranged in the path of the tape so as to deflect it when the leading end of the tape is thrust against it. The deflection is upward, and permits the tape to be easily grasped by the fingers to be drawn forth as much as desired. The moistener 13 is represented as a roller having stub axles 75 17 mounted in bearings 18 provided in the inner face of the vertical walls of the pan 14. This pan may extend forward and be covered with a sliding plate 18, as illustrated, and can extend backward as far toward or 30 under the bed of rollers 15, as desired. As illustrated, it is removable through the top of the frame when the slide cover 19 has been removed; and it is prevented from falling through the bottom of the apparatus by 35 clips or lugs 20. Other arrangements of knife and roller may, however, be used, such as those in which the moistener precedes the severing means, or in which the latter is of a different type, or is positioned at a greater 40 distance from the path of the tape, all of which constitute arrangements already well known.

The invention also provides means for producing a nicely determined and proper 95 tension for the tape. The elimination of deterrent friction in the feeding means of the tape contributes to this, and the elimination of friction on the supply roller contributes, leaving the net or total tension to be determined by a suitable device which is added 100 for that purpose, providing a determinable friction, which in the present case consists of a simple spring 21 pressing against the tape as it passes around a guide roller 22, located at the end of the frame remote from the moistening tank and suitably positioned in journals in standard 11 and a low standard 24 with respect to the supply holding standard 11 so that tape coming from the 105 supply roll thereon can pass around under the guide and thence go over the bed of rollers 15. Below this guide roller, and pressing up against it, is the spring 21 mounted, as by screws 23, on the frame 10. The degree of pressure can be pre-determined by the relation in which the parts are set, the stiffness and bend of the spring, etc., as will 110 be readily understood by any person of ordinary skill in mechanics.

Another feature of the invention consists of the device by which the supply roll 9 is relieved of frictional drag, or is provided with the desired small amount thereof to counteract the effect of momentum, and by which this can be set permanently so as to be the same upon rolls of tape of equal size introduced into the apparatus in succession, as one after another becomes exhausted, without disturbance and re-setting. To this 115 120 125 130

end the upper part of the standard 11 carries a horizontal stud 25 which extends across the apparatus and constitutes a stationary axle on which the wooden core 26 is customarily provided in rolls of paper tape turns loosely. This stud is threaded far enough to permit the screw nut 27 and the non-rotating washer 28 upon it to be moved as close to the standard 11 as is required for 10 holding the narrowest tape which the apparatus is intended to hold. The stud may have a flat side 25' corresponding to a flat side and hole through the washer, as seen in Figs. 5 and 6, so that the latter cannot 15 rotate upon it. The nut and washer may then be set to provide any desired drag to prevent unwinding of the supply roll, due to momentum consequent upon the drawing forth of tape; or can be set so as to apply 20 no friction of this nature but merely to hold the roll in position at the base of the stud; and thus to hold the tape steady and to start it in a straight path through the apparatus. The substitution of a full for an exhausted 25 roll without disturbing this adjustment is provided by making a shoulder 25'' on the pin, the reduced diameter made by the shoulder being the part which passes through the standard and being screw 30 threaded, as at 25''' and having a nut 29 on the outer side of the standard. Removal of this nut to the right in Fig. 5, permits the stud 25 to be taken out to the left, from the standard 11, and the supply roll core 26 can 35 then be slipped on to or off from the stud 25 without disturbing the nut 27 or the washer 28. This screw may be very short, while the screw on the part of the stud where the supply roll rests ordinarily has to 40 be as long as the full width of the apparatus. Hence the operation of replacing an exhausted roll, with the apparatus of the invention, is very quickly performed and does not disturb the adjustment of frictional 45 drag or of position of the roll; for if the new roll be of the same width as the old, and if the nut 27 on the stud 25 has not been disturbed, the stud 25 when restored will be re-seated with precisely the same distance as 50 before between that standard and the nut 27.

The invention therefore provides a holder and feeding means by which the tape is under a definite pre-determined tension at all times regardless of the size of the supply 55 roll and regardless of conditions of humidity in the atmosphere which might cause more friction on or adhesion to the bed over which it is moved toward the moistener by pressure of the operator's finger. The working tension need be but little. The elimination of friction, which usually heretofore has been of varying and uncertain degree on the roll, and the elimination of sticking of 60 the tape where it is fed by the person's fingers, result in producing an easy running 65

apparatus with enhanced comfort and convenience in use. Tape of any width may be employed, up to the capacity of the machine; and rolls of tape in which the gum side is inward or those in which the gum side is outward may be employed, by reason that the guide roll 22 will take tape either from the forward or the rearward side of the roll 9.

The rear portion of the apparatus is preferably made lower than the forward portion, with the bed of rollers 15 extending up a slight incline. This makes it more natural that the forward moving finger of the operator presses against the side of each roll 80 15, and also produces a somewhat less expensive apparatus.

I claim as my invention:—

1. In a tape handling apparatus, a device 25 for facilitating feed of the tape, comprising a series of closely adjacent rollers over whose crests the tape passes and which in combination constitute a support with movable surface on which the tape is exposed to contact with a feeding finger.

2. In a tape handling apparatus, a device 90 for facilitating feed of the tape, comprising a series of closely adjacent rollers over whose crests the tape passes and which in combination constitute a support with movable surface on which the tape is exposed to contact with a feeding finger, said rollers being arranged with their axes in a plane.

3. In a tape handling apparatus, a device 100 for facilitating feed of the tape, comprising a series of closely adjacent rollers over whose crests the tape passes and which in combination constitute a support with movable surface on which the tape is exposed to contact with a feeding finger, the portions of 105 said rollers contacting with the tape being a multiplicity of points separated from each other.

4. In a tape handling apparatus the combination, with means for holding a tape supply, of a feed device having a movable surface over which the tape passes and means whereby the friction between the tape and the said surface is greater than the friction between the feed device having the said surface and its support, whereby the said tape and surface move together, and the frictional slip occurs between said feed device and its support.

5. In a tape handling apparatus, a self-clearing feeding device, comprising a surface whereon the tape is exposed to contact with a feeding finger; said surface being a composite of a plurality of elements constrained to move in paths momentarily supporting and then departing from the tape resting on the device.

6. Tape handling apparatus having a support for a supply roll of tape and means for engaging the tape to feed it therefrom, the 130

4
said roll and the said feeding apparatus being adapted to pass the tape approximately without drag, due to deterrent friction; and a spring drag applicable to the tape between 5 the supply roll and the feeding device.

7. Tape handling apparatus having a holder for a supply roll of tape comprising a standard, a pin projecting therefrom, having a roll holding portion adapted to pass 10 through the supply roll at its axis and another portion removably secured to the standard; means on the roll holding portion delimiting a part thereof for the supply roll; means whereby the supply roll is 15 placeable over the secured portion of the pin.

8. Tape handling apparatus having a holder for a supply roll of tape comprising a standard; a pin of two diameters, one for 20 passing through the supply roll axially, and the other, smaller, passing through the standard, with a shoulder between its larger and smaller portions and fastening means on the latter portion; the parts being so adapt- 25 ed to each other in size that the supply roll is removable over said shoulder, whereby replacement of a supply roll need not vary the roll holding space.

9. Tape handling apparatus comprising means to hold a supply roll of tape; a tape-compressing tension apparatus through which the tape passes from the supply roll, fixed in position and constituting frictional tension means; and a support having a freely movable surface over which the tape passes, 35 adapted for movement with the tape in the direction of tape feeding, and constituting a feeding device.

10. Tape handling apparatus comprising means to hold a supply roll of tape; a tape-compressing tension device through which the tape passes from the supply roll, fixed in position and constituting a frictional drag; a tape support having a movable surface over which the tape passes, constituting a 45 feeding device; a tape severing device, and a moistener; the said movable surface being arranged and adapted to direct the tape against said moistener.

Signed by me at 52 Vanderbilt ave., New 50 York, N Y., this 31st day of January, 1918.
